UNITED STATES PATENT OFFICE

ROBERT G. COLLINS, OF PHILADELPHIA, PENNSYLVANIA

BINDER STRIP FOR FLOOR COVERINGS

Application filed September 7, 1929. Serial No. 290,877.

My invention relates to a new and useful binder strip for floor coverings whereby the borders or edges of such coverings are completely enclosed and protected to prevent 5 wear and tear and to prevent ruffling, wrinkling, and curling thereof, and whereby two or more separate pieces of floor coverings may be detachably and flexibly joined.

As is well known, the edges of floor coverings are frequently subject to excessive wear and tear as compared to the body portions thereof. Furthermore, due to the tendency of the edges of floor coverings to curl upwardly, and become wrinkled and ruffled, an untidy appearance results, together with a constant risk of stumbling over said edges and a certain amount of interference with the opening and closing of doors and the moving about of the furniture. These disadvantages are greatly accentuated in the case of rubber and other mats or rugs and other relatively thin, light floor coverings to an extent which frequently necessitated the tacking down or nailing of such floor coverings to the floor, with consequent damage to the floor and the floor coverings.

It has further been the practice, when it is desired to join two or more pieces of floor coverings to form a single piece, to sew, interweave, or tack the adjacent edges of said floor coverings together, with consequent damage to the floor and floor coverings and with a resultant difficulty in separating or detaching the floor coverings thus joined when and if desired.

It is the object of my invention to provide novel binder attached strips, whereby the edges of floor coverings are completely enclosed and protected to prevent wear and tear, and whereby such edges are weighted down against the floor to prevent wrinkling, curling, and ruffling without the necessity of permanently fastening the edges of said floor coverings to the floor, and at the same time 45 eliminating the risk of stumbling over said edges.

A further object of my invention is to provide means for detachably joining the adjacent juxtaposed edges of two pieces of floor coverings to form a continuous single piece

without the necessity of sewing, interweaving, or tacking.

To the above ends, my invention consists of an inner U-shaped sleeve adapted to be rigidly and permanently secured to the edge 55 of a floor covering, a weight in or in proximity to said inner sleeve, a slightly larger outer U-shaped sleeve slidable over and adapted to enclose said inner sleeve, means for interlocking said inner and outer sleeves 60 in assembled position, and end cover clips adapted to engage and close the opposed open ends of said outer sleeve.

My invention further consists of novel means for detachably joining the adjacent 65 edges of two pieces of floor coverings comprising U-shaped couplings adapted to engage the juxtaposed ends of the outer sleeves on said floor coverings, whereby the protected and enclosed edges of two floor coverings, 70 such as a pair of runners, may be joined in a flexible but detachable manner without any damage or injury thereto.

My invention still further consists of various other novel features of construction 75 and advantage, all as hereinafter described and claimed.

For the purpose of illustrating my invention I have shown in the accompanying drawings two forms thereof which are at present 80 preferred by me, since the same have been found in practice to give satisfactory and reliable results, although it is to be understood that the various instrumentalities of which my invention consists can be variously arranged and organized and that my invention is not limited to the precise arrangement and organization of the instrumentalities as herein shown and described.

In the accompanying drawings: 90

Fig. 1 represents a plan view of a floor covering provided with end binder strips embodying my invention, certain parts being shown in section.

Fig. 2 represents a fragmentary plan view 95 illustrating the construction and manner of assembly.

Fig. 3 represents on an enlarged scale a section on line 3—3 of Fig. 1.

Fig. 4 represents a perspective view of an 100

end clip shown at the top and bottom extremities of Fig. 2.

Fig. 5 represents a plan view, partly in section, illustrating the use of my novel binder strips for the purpose of joining the adjacent ends or edges of two runners.

Fig. 6 represents a side elevation of the connecting U-shaped coupling or clip employed in the construction illustrated in Fig. 5.

Referring to the drawings, in which like reference characters indicate like parts, 1 designates a runner, rug, or mat of rubber, wool, or other material, the edges of which are provided with binder strips embodying my invention and comprising the inner U-shaped sleeve 2 having the inwardly deflected or folded edges 3 and secured to the edge 4 of the runner 1 by the bolt, pin, rivet or its equivalent 5. In the outer portion of the U-shaped sleeve 2 is the weight 5a, such as a bar of lead or the like, which serves to weight down the edge 4 of the runner 1, as will be hereinafter explained. An outer U-shaped sleeve 6 having the inwardly deflected edges 7, forming ways for the edges of the inner sleeve 2, is adapted to slide over and enclose the inner U-shaped sleeve 2 and is locked in position by the locking rod 8, which is positioned in the chamber formed between the closed ends of the two sleeves. The outer ends of the outer U-shaped sleeves 6 are enclosed by the U-shaped clips 9 to impart a neat and attractive appearance and to prevent the entry of dust and dirt, as will be understood from Figs. 1, 2, and 5.

To remove the outer sleeve 6 it is first necessary to withdraw or remove the clips 9, after which the rod 8 is withdrawn, whereupon the outer sleeve 6 slides easily over the inner sleeve 2 and is longitudinally withdrawn, as will be understood from Fig. 2.

When it is desired to join the ends or edges of two adjacent runners or rugs 13 and 14 provided with my novel binder strip, it is merely necessary to shorten the locking rods 8, to provide recesses at either end thereof for receiving the U-shaped couplings 10, the arms 11 and 12 of which are adapted to engage the parallel recesses formed in the adjacent edges of the juxtaposed outer U-shaped sleeves 6; thus flexibly and detachably joining the runners or rugs 13 and 14, as will be understood from Fig. 5.

By use of the outer sleeves 6 of highly polished brass or other metal, I not only impart an attractive appearance to my novel binder strips, but I cover the bolts 5 securing the inner sleeve 2 to the edge 4 of the rug 1, and thus guard against scratching or otherwise damaging the hardwood floor upon which said rug is laid.

It will thus be seen that I have devised a novel binder strip whereby all ruffling, curling and wrinkling of the edges of floor coverings is eliminated, so that a neat and attrac-

tive appearance is presented, and all risk of stumbling over edges of floor coverings, and all interference with the closing and opening of doors or the moving about of furniture is obviated, since the edges of floor coverings, whether fringed or hemmed, are thus compressed into a relatively flat U-shaped sleeve which forms no serious obstruction as is the case with the loose, unprotected and unenclosed edge of floor coverings as conventionally laid on floors. The protection from wear and tear and the increase in the life of the floor coverings is obvious.

I am aware that the invention may be embodied in other specific forms without departing from the spirit or essential attributes thereof, and I therefore desire the present embodiment to be considered in all respects as illustrative reference being had to the appended claims rather than to the foregoing description to indicate the scope of the invention.

Having thus described my invention, what I claim as new, and desire to secure by Letters Patent, is:

1. In a device of the character stated, an outer U-shaped sleeve having its inner edges folded inwardly to form inner ways, an inner sleeve having its edges positioned within said ways, there being a chamber formed between the closed ends of said sleeves, and a longitudinally slidable locking rod positioned in said chamber.

2. In a device of the character stated, an outer U-shaped sleeve having its inner edges folded inwardly to form inner ways, an inner sleeve having its edges positioned within said ways, there being a chamber formed between the closed ends of said sleeves, a longitudinally slidable locking rod positioned in said chamber, and a floor covering having its edge positioned within said inner sleeve and secured thereto.

3. In a device of the character stated, an inner U-shaped sleeve adapted to engage the edge of a floor covering, means for securing said sleeve to said edge, a weight in said sleeve, an outer U-shaped sleeve slidable over and adapted to enclose said inner sleeve, and means for interlocking the edges of said inner and outer sleeves.

4. In a device of the character stated, an inner U-shaped sleeve adapted to engage the edge of a floor covering, means for fastening said sleeve to said edge, a weight in said sleeve, an outer U-shaped sleeve slidable over and adapted to enclose said inner U-shaped sleeve, means for interlocking said inner and outer sleeves, and U-shaped end clips adapted to engage and enclose the ends of said sleeves.

5. In a device of the character stated, a pair of inner U-shaped sleeves adapted to enclose the adjacent edges of two contiguous pieces of floor covering, means for securing said inner sleeves to said edges, a pair of

outer **U**-shaped sleeves slidable over and adapted to enclose said inner sleeves, means for interlocking said inner and outer sleeves, **U**-shaped clips adapted to engage and enclose the ends of said sleeves, and **U**-shaped couplings adapted to engage the juxtaposed adjacent edges of said outer sleeves flexibly and detachably to join said edges.

6. In a device of the character stated, a
10 pair of inner **U**-shaped sleeves adapted to enclose the adjacent edges of two contiguous pieces of floor covering, means for securing said inner sleeves to said edges, weights in said inner sleeves, a pair of outer **U**-shaped
15 sleeves slidable over and adapted to enclose said inner sleeves, means for interlocking said inner and outer sleeves, **U**-shaped clips adapted to engage and enclose the ends of said sleeves, and **U**-shaped couplings adapted to
20 engage the juxtaposed adjacent edges of said outer sleeves flexibly and detachably to join said edges.

7. A binder strip for floor coverings comprising an outer **U**-shaped sleeve having its
25 inner edges folded inwardly to form inner ways, an inner sleeve telescoping within said outer sleeve and having its edges positioned in said ways, there being a chamber formed between the closed ends of said sleeves, a longitudinally slidable locking rod positioned in said chamber, a weight for one of said sleeves, and a flexible coupling adapted to engage the end of said locking rod chamber, detachably and yieldably to join two adjacent
30 binder strips.
